(57) **CLAIM**

We claim the ornamental design for an expanded space shower tub and bathtub, as shown and described.

DESCRIPTION

FIG. 1 is a rear perspective view of the expanded space shower tub and bathtub, shown with an inwardly cantilevered apron deck;

FIG. 2 is a front perspective view of the expanded space shower tub and bathtub, shown with an inwardly cantilevered apron deck;

FIG. 3 is a front elevation view of the expanded space shower tub and bathtub;

FIG. 4 is a rear elevation view of the expanded space shower tub and bathtub, showing dashed lines for the disclaimed rear wall, which is shown for environmental purposes;

FIG. 5 is a left side end elevation view of the expanded space shower tub and bathtub; showing dashed circular lines for the disclaimed trip lever hole, which is shown for environmental purposes;

FIG. 6 is a right side end elevation view of the expanded space shower tub and bathtub;

FIG. 7 is a cross-sectional right side end view of the expanded space shower tub and bathtub; shown with an inwardly cantilevered apron deck, showing dashed circular lines for the disclaimed trip lever hole, which is shown for environmental purposes, and where this view is taken along directional arrow view lines "7-7" shown in FIG. 1;

FIG. 8 is a top plan view of the expanded space shower tub and bathtub, shown with an inwardly cantilevered apron deck and angled back rest, and also showing dashed circular lines for the disclaimed drain hole and dashed oval lines for the disclaimed trip lever hole, which are shown for environmental purposes;

FIG. 9 is a close-up perspective cross-sectional detail view of a portion of the inwardly cantilevered apron deck portion of the expanded space shower tub and bathtub, and where this view is taken along directional arrow view lines "9-9" shown in FIG. 1; and,

FIG. 10 is a rear cross-sectional view of the expanded space shower tub and bathtub, shown with an inwardly cantilevered apron deck and angled back rest, and where this view is taken along directional arrow view lines "10-10" shown in FIG. 1. The depiction of the rear wall, trip lever hole and drain hole, shown in dashed lines on the expanded space shower tub and bathtub, are shown for environmental purposes, and form no part of the claimed design.
